UNITED STATES PATENT OFFICE.

FRANK E. JONES, OF KIRKWOOD, ILLINOIS.

DESIGN FOR A PAPER BOX.

SPECIFICATION forming part of Design No. 28,042, dated December 14, 1897.

Application filed October 16, 1897. Serial No. 655,482. Term of patent 3½ years.

To all whom it may concern.

Be it known that I, FRANK E. JONES, a citizen of the United States, residing at Kirkwood, in the county of Warren and State of Illinois, have invented and produced a new and original Design for a Paper Box, of which the following is a specification, reference being had to the accompanying drawings, forming part thereof.

10 In the drawings, Figure 1 is a view in perspective of a paper box, showing my new design. Fig. 2 is an end view thereof.

The leading feature of my design consists in a paper box shaped and ornamented to 15 represent a sofa or lounge.

The letter A designates the upper side, B the front side, C the rear side, and D and E the two ends, of the box. The end D is extended upwardly beyond the upper side A

and slightly bent outwardly to represent the 20 head-rest of the sofa or lounge, and the rear side C is extended upwardly and curved at its upper edge to represent the back of the sofa or lounge. The said back, head-rest, and upper side A are ornamented with lines 25 to represent upholstering, and the sides and ends of the box are ornamented with lines to represent the frame and four legs of the sofa or lounge.

I claim—

30 The design for a paper box substantially as herein shown and described.

In testimony whereof I affix my signature in presence of two witnesses.

FRANK E. JONES.
